UNITED STATES PATENT OFFICE.

JOHN DE MOOY, JR., AND WILLIAM H. CLEMES, OF CLEVELAND, OHIO, ASSIGNEES TO THE TAYTOR & BOGGIS FOUNDRY COMPANY, OF SAME PLACE.

OIL-STOVE.

SPECIFICATION forming part of Letters Patent No. 511,737, dated December 26, 1893.

Application filed February 27, 1893. Serial No. 463,793. (No model.)

To all whom it may concern:

Be it known that we, JOHN DE MOOY, Jr., and WILLIAM H. CLEMES, citizens of the United States, and residents of Cleveland, county of 5 Cuyahoga, and State of Ohio, have invented certain new and useful Improvements in Oil-Stoves, of which the following is a specification, the principle of the invention being herein explained and the best mode in which 10 we have contemplated applying that principle, so as to distinguish it from other inventions.

The annexed drawings and the following description set forth in detail, one mechanical 15 form embodying the invention; such detail construction being but one of various mechanical forms in which the principle of the invention may be used.

In said annexed drawings—Figure I represents a perspective view of our improved oil stove; Fig. II, a transverse section of the same; Fig. III, a longitudinal section of the stove; Fig. IV, a top plan view of the cone-stand, and Fig. V, a perspective view of the inverted 25 cone-stand.

The fount A, is of any suitable or desired construction, and is disclosed in the drawings as cast integrally and in one piece. The top of said fount is formed with an oblong neck, 30 a, with two lugs, a' a', at each side of the middle of said neck, and with the usual filling opening, a''. The lugs a' are formed with vertical screw-threaded holes.

A combined cone-stand, wick tube and handle, B, cast in one piece, is secured to the neck by means of screws, b, which pass through cross bars, b', extending between the lower portion of the wick tube and the cone-stand. The wick tube B' is formed with a rabbet, b'', 35 in the bottom end, and fits with such rabbet upon the upper end of the neck of the fount; and the wick tube has, furthermore, an enlargement, b'', in one side of its wick passage,—such enlargement forming a cylinder segment 40 and constituting a housing for the wick raiser. The wick raiser C, is journaled with its shaft, C', in a notch, b'', in one end of the rabbet of the wick tube, and in a notch, b'', which extends through the opposite end of the wick

tube. The wick raiser has the usual fluted 50 head, C'', and the usual ratchets, c. The cone-stand B'' is formed with a rabbet, b'', in its upper side, and the usual perforated plate, B'', is supported in said rabbet. The cone-stand has, at one side, two projecting and perforated ears, b''; and, at the other side, the handle B' projects from the cone-stand, forming a continuation of one of the connecting cross bars. A recess, b'', is formed at the inner end 55 of the handle, serving to accommodate the latch spring, D, which will later be more fully described.

The cone-plate, E, is cast in about the usual form, and fits upon the upper side of the cone-stand. Said cone-plate has, at one side, two 60 projecting lugs, e, which engage the perforated ears of the cone-stand, and form,—together with said ears,—a detachable hinge between the cone-stand and the cone-plate and stove top. A catch lug, e', projects at the opposite 65 side of the cone-plate, and may engage a perforation, d, in the latch spring D. Said latch spring is secured with its lower, bent and perforated end, upon one of the cross bars of the cone-stand, by means of one of the screws b, 70 which secure the cone-stand to the neck of the fount. The latch spring has play in the recess b'', so that it may be pulled outward and be disengaged from the catch lug, when it is desired to tilt the stove top. 75

The chimney F, and the top grate G, are of the usual, or any preferred form, and form no part of our present invention.

By constructing the parts of our oil stove as above described, we attain great simplicity 80 of structure, and economy in the putting together of the several parts; and the wick raiser is very conveniently journaled in the notched bearings between the cone-stand and the neck of the fount. 85

All parts of the stove, with the exception of the wick raiser, the latch spring, and the chimney, are cast, and the parts may be assembled very quickly and simply.

Other modes of applying the principle of 90 our invention may be employed for the mode herein explained. Change may therefore be made as regards the mechanism thus dis-

closed, provided the principles of construction set forth respectively in the following claims are employed.

We therefore particularly point out and 5 distinctly claim as our invention—

1. In an oil stove, the combination of a fount having a neck for the passage of the wick, a wick tube secured to the top of said neck and formed with notched bearings in its 10 ends, and a wick raiser having its shaft journaled in such notched bearings, substantially as set forth.

2. In an oil stove, the combination of a fount having an oblong neck for the passage 15 of the wick, a wick tube formed with a rabbet in its bottom end and with notched bearings in the lower edges of its ends,—said wick tube being secured to the top of the neck with its rabbet fitting over said neck,—and a wick 20 raiser having its shaft journaled in the notched bearings, substantially as set forth.

3. In an oil stove, a cone-stand and wick tube formed integrally in one piece, and having cross bars which extend from the middles 25 of both sides of the wick tube to the middles of the sides of the cone-stand, substantially as set forth.

4. In an oil stove, a cone-stand, wick tube and handle formed integrally in one piece, 30 said cone stand and wick tube having cross bars extending between the middles of their sides, and said handle forming a continuation of one of said cross bars, substantially as set forth.

35 5. In an oil stove, the combination of a

fount having an oblong neck and a screw-threaded perforation, a wick tube and cone-stand having a perforated cross bar registering with said screw-threaded perforation and having a handle forming a continuation of 40 said cross bar, a latch spring having a bent and perforated lower end, and a screw passing through said spring, cross bar and screw-threaded perforation, substantially as set forth.

6. In an oil stove, the combination of a wick tube and cone-stand formed with a perforated cross bar and a handle continuing said cross bar, and formed with a recess at the inner end of the handle, and a latch spring secured to said cross bar and having play in the recess of the cone-stand, substantially as 45 set forth.

7. In an oil stove, the combination of a cone stand and having a perforated cross bar and 50 a handle, a fount having a screw-threaded perforation registering with said cross bar, a latch spring having a perforated lower end, and a screw passing through said latch spring, cross bar and screw-threaded perforation, securing 55 the parts together, substantially as set forth.

In testimony that we claim the foregoing to be our invention we have hereunto set our hands this 25th day of February, A. D. 1893.

JOHN DE MOOY, JR.
WM. H. CLEMES.
